UNITED STATES PATENT OFFICE.

AUGUSTUS LOTZ, OF SAN FRANCISCO, CALIFORNIA, AND CLARENCE W. BAILEY, OF PHILADELPHIA, PENNSYLVANIA, ASSIGNEES, BY MESNE ASSIGNMENTS, TO THE VACUUM CLEANER COMPANY, OF NEW YORK, N. Y., A CORPORATION OF NEW YORK.

GOVERNOR FOR VACUUM CLEANING SYSTEMS.

1,128,615.

Specification of Letters Patent. Patented Feb. 16, 1915.

Application filed December 30, 1907. Serial No. 408,525.

To all whom it may concern:

Be it known that we, AUGUSTUS LOTZ and CLARENCE W. BAILEY, citizens of the United States, said Lorz being a resident of the city and county of San Francisco, State of California, and said BAILEY a resident of the city and county of Philadelphia, State of Pennsylvania, have invented new and useful Improvements in Governors for Vacuum Cleaning Systems, of which the following is a specification.

Our invention relates to improvements in vacuum cleaning systems, its object being to provide automatic control of the vacuum creating means determined by the degree of vacuum in the system. The purpose of this is to vary the action of the vacuum creating means proportionate to the variation in the vacuum in the system due to the variable air inlet thereto. In such a system, provided with power adequate for the operation of a given number of sweepers operating at a predetermined degree of vacuum, in case the number of sweepers at any time in action be less than the maximum, the vacuum creating means would, if unchecked, produce excessive vacuum in the system. Consequently it is important for the sake of economy, that when such excessive vacuum is attained, the creating means be checked, and the operating power thereby economized proportionately to the requirements upon the system.

In the accompanying drawings forming part hereof, Figure 1 is a conventional drawing of a vacuum sweeping system provided with our improved governor, and Fig. 2 is a longitudinal, sectional, detail of the governing devices shown connected with the engine governor.

A represents the engine, B the vacuum pump, C the wet separator tank, D the dry separator tank, E a sweeper, F the engine governor and G our improved vacuum governor. The engine is operatively connected to the pump by means of the rod 2. The pump is connected with the tank C by the pipe 3, the tank C with the tank D by the pipe 4, and the tank D with the stand-pipe 5 by the pipe 6.

7 is the hose coupling upon the stand-pipe 5, 8 the hose leading therefrom to the handle 9 of the sweeper E. 10 is a manually

operated valve upon said handle for cutting off communication between the sweeper 35 and the hose.

11 is a pipe connecting the tank C with the vacuum governor G.

12 is a pipe leading from the boiler to the steam chest 13, and provided with a 60 valve 14 controlled by the engine governor F of the top.

Operatively connected with the valve stem 15, is the piston 16 working in the cylinder 17 of the governor G. This piston is 65 connected by means of the link 17' with the pivoted lever 18, the other end of which lever is connected by the link 19 with the long arm of the pivoted lever 20, the other end of which engages the stem 15 of the 70 governor G. The lower end of the cylinder 17 is open to the atmosphere and the adjustable stop 21 limits the upward movement of the piston 16. In the upper end of the casing of the governor G, is a cylinder 22 75 in which is loosely arranged the weight 23 carried upon rod 24, the upper end 25 of which is a piston working in the cylinder 26 of the head 27. This cylinder 26 is connected as shown in Fig. 1 with the pipe 11 80 leading to the tank C. The piston 25 has an axial passage 28 leading to lateral vents 29, opening into a circumferential groove 30, which, when the piston is at its upper limit of travel, communicates with the passage 31 leading to the port 32, opening into the cylinder 17. The piston 25 has also a circumferential groove 33 which when the piston is at the lower limit of its movement 85 opens communication between the passage 31 and the outlet port 34 opening to the atmosphere.

The position of the parts shown in Fig. 2 is that assumed when excessive vacuum in the system has overcome the gravity of the 95 block 23, and has lifted it so as to open communication between the system and the cylinder 17 causing the piston 16 to move upward to its limit and by means of its connections above described, to act upon the 100 valve stem 15 to partially close the valve 14, thereby cutting off steam from the engine and lowering its speed. By adjusting the stop 21 and modifying the dimensions of the passage 31, this action may be made as 105 gradual, and limited as desired, the speed of

the engine and pump being varied to correspond with the requirements of the system, thereby economizing the power.

In use the piston 16 under the influence 5 of its own gravity normally rests at the bottom of its cylinder. The weight 23 also rests at the bottom of its chamber, the groove 33 upon the piston 25 affording communication between the cylinder 17 and the 10 atmosphere, the engine being supplied with the full amount of steam and it and the pump running at normal speed. In case one or more of the valves 10 in the handles of the sweepers E are turned to cut off the 15 sweepers from the system, the inflow of air is proportionately diminished, and the vacuum in the system increased. When it exceeds the predetermined maximum the suction upon the piston 25 overcomes the weight 20 23, and the piston moves upward to the position shown in Fig. 2, thereby cutting off communication between the cylinder 17 and the atmosphere, and opening communication between the system and the cylinder. 25 The action of the vacuum upon the piston 16 lifts it and causes it through the connected parts, to actuate the valve stem 15 to partially close the valve 14, thereby lessening the flow of steam to the engine and lowering 30 the speed of both engine and pump until the vacuum in the system falls sufficiently to allow the weight 23 to drop, and open communication between the cylinder 17 and the atmosphere, when the piston 16 drops, restoring the normal position of parts and 35 again admitting the full complement of steam to the engine.

We claim:

1. In a vacuum cleaning system, having a 40 variable air inlet, a pump, an engine for driving said pump, a valve controlling the supply of steam to said engine, a cylinder, a piston working therein and operatively

connected to said steam valve, means for adjustably limiting the travel of said piston to close said valve, a conduit leading to said cylinder, a three-way piston valve adapted to connect said conduit with said system or the atmosphere, a weight holding said valve normally in position to maintain 45 communication between said conduit and the atmosphere, said valve being adapted to be actuated by excessive vacuum in said system to close communication between said conduit and the atmosphere and to open 50 communication between said conduit and said system to actuate said piston.

2. In a vacuum cleaning system having a variable air inlet, a vacuum pump, a steam engine for driving said pump, a valve controlling the flow of steam to said engine, a pressure-operated member operatively connected to said steam valve and itself actuated by variations between atmospheric pressure and the pressure in said system, a 60 three-way auxiliary valve adapted to connect said pressure-operated member with the system or the atmosphere, a weight for holding said auxiliary valve in position to maintain communication between said pressure-operated member and the atmosphere, said auxiliary valve being adapted to be actuated by excessive vacuum in the system to cut off communication between said pressure-operated member and the atmosphere 65 and to open communication between it and the system, as and for the purposes specified. 70

In testimony whereof we have hereunto set our hands this 23rd day of December, 80 1907.

AUGUSTUS LOTZ.

CLARENCE W. BAILEY.
